United States Patent Office.

DOMINICO CHEEKENI, OF BROOKLYN, NEW YORK.

Letters Patent No. 65,644, dated June 11, 1867; antedated June 5, 1867.

TOY ROPE-DANCER.

The Schedule referred to in these Letters Patent and making part of the same.

TO ALL PERSONS TO WHOM THESE PRESENTS SHALL COME:

Be it known that I, DOMINICO CHEEKENI, of Brooklyn, Kings county, and State of New York, have invented a new Rope-Dancer or Toy for Children; and do hereby declare that the following is a full, clear, and exact description of the same, reference being had to the accompanying drawing, which represents a perspective view of my invention.

This invention relates to a novel device by which a figure representing a rope-dancer is made to perform peculiar movements; and consists of a platform to which are attached cross-trees for sustaining a rope, and a back rest for the dancer, together with a rectangular lever, having at one end the rope-dancing figure, and at the other a set of bells and a finger-plate, so that when the finger-plate is pressed upon by a person's finger and raised alternately, the bells will ring, making music, while at the same time the dancing figure performs its movements on the rope.

In the said drawings, A represents a hollow platform or box, which sustains the cross-trees B B to which are attached the back rest C and rope D, on which the figure dances. There is also attached to the interior of said platform a rectangular-shaped lever, E, which plays in a fulcrum, F, connected with the platform. This lever E has on its forward end a finger-plate, G, which projects a short distance above the platform, and is for the purpose of operating the lever; and attached to said end is a series of bells, H, which are rung on pressing the finger-plate G, while on the other end of said lever is placed the rope-dancing figure I, holding a balance-pole, K.

The operation of my invention is as follows: The figure I being placed face to face with the operator, now, by pressing the plate G downward with and quickly raising the finger, the plate G will follow the finger in its ascent, because of the weight of the figure I at the opposite end of the lever E, and this movement of the finger-plate will impart to the figure I, (through the lever E,) the up-and-down or dancing movements, and will also vibrate and ring the bells H attached to the forward end of said lever, thus making music during the performance of the rope-dancing figure I.

I would here remark that the dancing figure I may be composed entirely or in part of paper, India rubber, or any other suitable material, as well as of wax, and may also be made to represent other characters, male or female. Furthermore the cross-trees B B, instead of being rigidly fastened, may be hinged to the platform and folded on the same, and the figure placed within the platform for convenience in transportation.

Having described my invention, what I claim, and desire to secure by Letters Patent, is—

The lever E, the bells H, the rope D, and figure I, or its equivalent, in combination with the cross-trees B B and platform A, substantially as and for the purposes described and set forth.

In testimony whereof I have hereunto set my signature.

DOMINICO CHEEKENI.
